Filed Mar. 11, 1971, Ser. No. 123,494

Term of patent 14 years

Int. Cl. D30—03
U.S. Cl. D30—13

FIG. 1 is a perspective view of a poultry cage feeder, showing one form of my new design with pipe curved at one end;

FIG. 2 is an end elevational view showing a second form with straight pipe;

FIG. 3 is a fragmentary top plan view, a portion being removed and omitted for convenience in illustration, showing a third form with pipe curved at both ends;

FIG. 4 is a cross-sectional view, to an enlarged scale, taken on line 4—4 in FIG. 1; and

FIG. 5 is a fragmentary top plan view of a chain link with disc, to an enlarged scale.

I claim:

The ornamental design for a poultry cage feeder, as shown and described.
